METHOD AND MEANS FOR STRAIGHTENING WEFT-THREADS.

1,384,213.

Specification of Letters Patent. Patented July 12, 1921.

Application filed June 29, 1920. Serial No. 392,676.

To all whom it may concern:

Be it known that I, WILLIAM S. ROWLEY, a citizen of the United States, and resident of West New Brighton, Staten Island, 5 county of Richmond, and State of New York, have invented an Improvement in Methods and Means for Straightening Weft-Threads, of which the following is a specification.

10 The object of my invention is to treat cloth, the weft threads of which are displaced angularly in respect to the selvages, in such manner that the ends of any weft thread adjacent to the two selvages of the 15 web of cloth may be brought into the same transverse alinement at right angles to the length of the web or in substantially the same line at right angles to either selvage, and also to cause the weft threads which 20 may be curved intermediate of the selvages to be advanced or moved back along the fabric web to insure them assuming a more or less approximately correct position in the woven web, the result of which treatments 25 permits the cloth to be properly fed to a tentering machine whose action speedily and fully brings the entire weft threads into straight parallel alinement and insures in the finished goods the weft threads positioned 30 at right angles to the warps.

In subjecting woven fabrics, after leaving the loom, to various processes prior to the final rolling of the cloth for shipment, each handling of the cloth has a tendency to dis- 35 tort and displace the weft threads out of their original straight transverse alinement which, in the woven fabric as it leaves the loom, is at right angles to the length of the warp. This displacement is not material 40 provided it is not excessive and the ends of the warp threads adjacent to the two selvages are in the same transverse alinement as they come from the loom, because any small intermediate twisting or displacing of 45 the weft threads may be straightened by treatment in the tentering machine before the final rolling for shipment. It, however, happens that in most cases, the ends of the weft threads become displaced to a greater 50 or less degree in fabrics which have been subjected to the various processes aforesaid so that the general trend of many of the weft threads is more or less diagonal and if not corrected will produce unsightly and un- 55 satisfactory cloth; and this objectionable

condition will not be removed by treatment in the tentering machine, because it is manifest that the ends of the same weft threads would not be held in clamps in the same transverse alinement and consequently the 60 distortion by displacement of the weft threads would not be rectified by treatment in the tentering machine even though the weft threads were more or less straightened as to their intermediate parts. 65

It is further to be understood that, aside from the fact that the two ends of the several weft threads adjacent to the two selvages of the woven fabric are, more or less, displaced in advance of each other, either at 70 one or the other side of the fabric, there is in addition to this defect a condition in which said weft threads ordinarily assume a greater or less curved shape intermediate of their ends, and my invention is particularly 75 intended to correct not only the displacement of the ends of the weft threads but also this curved arrangement of the weft threads at the portions of the fabric intermediate of its selvages; and it will be further understood that this curved condition of the weft threads will be presented to the machine 80 differently according to whether the curvature is displaced backward of the ends of the weft threads or in advance of them, and 85 hence my improved apparatus is designed to take care of these defects irrespective of which end of the fabric web may be fed to the machine in starting the treatment.

The special object of my invention, therefore, is to provide means through which the woven fabric may be fed and by which the weft threads thereof will be subjected to a straightening action, the machine having provision for causing the weft threads to be 90 advanced intermediate of the selvages and greatest at the central portion of the web; or reversely, to cause the weft threads adjacent to the selvages to advance more rapidly 95 than those portions thereof intermediate of the selvages, with the greatest retarding adjacent to the central portion of the web; and providing the machine further with means for causing the weft threads toward one selvage to advance more rapidly than the same 100 weft threads adjacent to the other selvage, said means having capacity for causing the operation of advancing the weft threads to take place at either selvage as may be required or to be shifted in its action from one 105 to the other. 110

side of the web to the other side, and vice versa, to bring the ends of the weft threads in the same transverse alinement.

My invention further consists in the method of treating the fabric for advancing or retarding definite portions of the weft threads wherein not only the weft threads adjacent to the selvages are advanced or retarded along the length of the cloth during its passage through the straightening machine in which it is subjected to treatment, but there is also such treatment of the weft threads that they are advanced or retarded uniformly on each side of the central line of the web to the same or substantially the same degree, the combined actions of said uniform treatment at each side of the central portion of the web and the concentration of the treatment of advancing the ends of the wefts adjacent to one selvage more rapidly than those adjacent to the other selvage, and vice versa, produces a composite result which not only insures the straightening of the weft threads as to their ends adjacent to the selvages but also the straightening of their intermediate curved portions to a greater or less extent as may be required.

My invention further consists of improvements hereinafter described whereby the above objects and results are attained, said improvements comprising certain operations upon the fabric, and also the organization and combination of parts constituting the machine, which are fully described hereinafter and more particularly defined in the claims.

Referring to the drawings: Figure 1 is a front elevation of a machine for straightening weft threads embodying my invention; Fig. 2 is a side elevation of the same; and Fig. 3 is a cross section of the same on the line $x-x$ of Fig. 2.

2 and 3 represent vertical beams extending from floor to ceiling and connected at intervals by horizontal frames 4; and similar frames are arranged at each side of the machine. Extending between the two side frames are a series of rollers of special construction and which are fully illustrated in Figs. 1 and 2. Secured to the upright frames 2 at each side of the machine are a series of bearings in which are journaled horizontal cylindrical guide rollers 5, 6, 7, 8 and 9. The fabric F passes under a transverse roller 31 thence upward in contact with the series of rollers 9, 8, 7, 6 and 5 in succession.

12 is a cylindrical roller which is arranged at an elevation intermediate of the levels of the guide rollers 8 and 9, and said roller 12 is journaled at each end in a bearing 17 which is pivoted on a vertical axis 19 to an adjustable slide 18, adjustably supported upon the lowermost horizontal frame

4 and adjustable by means of a horizontal screw shaft 20. This capacity for adjustment of each end of the roller 12 permits the roller to be adjusted at an angle to the alinement of the rollers 8 and 9 and at the same time to be adjusted to a position between them, as is indicated in dotted lines in Fig. 3. By this means the roller 12 may be adjusted to an angle with respect to the axes of the rollers 8 and 9; and either end of this roller 12, may be advanced relatively to the other end, according to whether the weft threads at one edge or the other edge of the fabric are displaced as to position and require treatment. To permit speedy adjustment of the screw shafts 20, they may be independently operated by means of vertical shafts 29 having cranks 27 at their lower ends and connected at their upper ends with the screw shafts 20 by miter gears 28. By revolving either one of the cranks 27, it is manifest that the corresponding end of the roller 12 may be advanced horizontally between the rollers 8 and 9 and in that manner put tension upon the fabric F, the tension being greater adjacent to one selvage than at the other and preferably said tension increasing gradually from one selvage to the other. This roller 12 is intended to subject the fabric to treatment which may bring the two ends of a displaced weft into the same transverse alinement and said alinement at right angles to the length of the selvage and warps.

Arranged above the roller 12 and at an elevation intermediate of the guide rollers 7 and 8, is a specially constructed roller 11 whose diameter decreases from its end to the middle and in such manner that the surface is more or less curved. This roller approximates two frusta of cones having longitudinal curved outer surfaces so as to avoid any abrupt change in surface at the center and moreover to provide greater tension action upon the fabric as the ends are approached. This roller 11 is journaled at each end in a bearing 13, which is adjustable horizontally along the middle transverse frame 4 and the adjustment is insured by a screw shaft 15. The construction is the same at each end of the machine and the screw shafts 15 are connected so as to revolve at the same speeds by means of a horizontal shaft 22 and bevel gears 21. By rotating the shaft 22, the two ends of the roller 11 are simultaneously advanced horizontally to any position between the rollers 7 and 8 which may be desired. This adjustment may be accomplished by means of the vertical shaft 24 having a crank 26 at the bottom and geared at 23 at the top to rotate the shaft 21. When this roller 11 is advanced between the rollers 7 and 8, it is manifest that its ends will first put tension upon the selvages of the fabric F and this tension may be increased by further 130

adjustment of the roller 11, and, if desired, until the middle portion of said roller acts upon the fabric. The extent of the action required of the roller 11 upon the fabric 5 would depend upon the extent to which the ends of the weft threads are displaced back of the middle portions of said threads and which ends are required to be advanced so as to bring the said ends and middle portions of the weft all into the same transverse alinement.

In addition to the roller 11, there is still a third roller 10 which is similarly supported and adjusted but at a higher elevation, 15 so as to operate upon the fabric intermediate of the guide rollers 6 and 7. In the case of this roller 10, it has a shape which is substantially a middle frustum of an elliptical spindle and having a curvature for its outer 20 surface substantially the inverse of the curvature of the roller 11. As will be seen from Fig. 1, the diameter of the roller 10 is smallest at the ends and greatest at the center and gradually decreases as the ends 25 are approached, but at such a rate that there is a longitudinal curvature given to the roller. The ends of roller 10 are journaled in slide bearings 13 carried upon the upper transverse frame 4 and adjustable by means 30 of screw shafts 14. These screw shafts 14 are coupled by a horizontal shaft 22 and bevel gears 21 and similarly to the operating means in respect to the roller 11; and further, shaft 22 for roller 10 is operated by 35 a vertical shaft 24 having a crank 25 at the bottom and a bevel gear 23 at the top for rotating the said shaft 22. All of the shafts 24 and 29 are supported in a bracket 30 extending from the upright frame 2, to support the cranks 25, 26 and 27 in convenient 40 position for operation.

The operation of this roller 10 upon the fabric web is the reverse to the action of the roller 11, in that its middle portion is 45 of the largest diameter and its circumference is gradually reduced as the two ends are approached. It is manifest that if the fabric is drawn against the roller 10, it will first contact with the middle portion and 50 then, by proper adjustment of said roller 10, be made to contact with more or less of the length of the roller to each side of its center, and the operation of this is to cause the weft threads at the middle portion of the fabric 55 to be advanced relatively to the portions of the same weft threads between the center and the selvages.

It is not intended, as a rule, to employ both rollers 10 and 11 upon the same web 60 of fabric at any one moment of time, because the curvature of the weft threads is generally in the same direction throughout the length of the fabric, and hence it will be amply sufficient to bring roller 10 or roller 65 11 into play according to which end of the

fabric is first fed into the machine. If the weft threads are curved with the middle portions in advance of the portions adjacent to the selvages, then roller 11 will be the one to be brought into play and roller 70 10 may be left out of action. If, however, the fabric had been turned end for end in starting it through the machine, then it would have been necessary to bring roller 10 into action and leave roller 11 out of 75 operation.

It will be understood that this machine has special capacity for straightening curved wefts, whether the curvature is in the direction of the travel of the fabric through 80 the machine or reversely; and when there is relative displacement in the wefts adjacent to the selvages, then the roller 12 is brought into play with its obliquity adjusted to insure the bringing into same transverse 85 alinement the opposite ends of the wefts. If the wefts are not curved but merely displaced to an angular position transversely of the web, then the roller 12 would be sufficient to rectify the defect without bringing 90 into play either rollers 10 or 11. It will be understood, therefore, that the machine has capacity for taking care of every character of defect due to displacement of the weft 95 threads.

I do not restrict myself to the direction in which the fabric passes through the machine, but by feeding it first over the guide roller 31 and thence upward passing the rollers 12, 11 and 10 successively, the necessity as to the particular manipulation of the rollers may be determined before the fabric reaches them. However, it will be understood that when the fabric is operating in the reverse direction, passing the rollers 105 10, 11 and 12 in succession, the operator may observe the fabric after treatment and adjust the rollers according to requirements to insure the most perfect results.

I have described my improved method and 110 means in that particularity which I deem to be the best exposition of my invention, and that which I prefer in commercial practice, but I do not restrict or confine myself to the minor or secondary details, as such variations may be resorted to as matters of mechanical skill and without a departure from the spirit of the invention.

It will now be apparent that I have devised a novel and useful construction which 120 embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent is:—

1. In a machine of the character stated, 5 the combination of a plurality of guide rollers for guiding a web of fabric, with means for straightening the weft threads of the fabric comprising a weft thread straightening roll having its largest diameter at the 10 middle and tapering toward its ends and movable against the fabric and between two of the guide rolls, a second weft straightening roll parallel to the first mentioned weft straightening roll and having its smallest 15 diameter adjacent to its middle portion and gradually increasing from the center toward each end and movable against the fabric and between two of the guide rolls, and independent means for adjusting the two weft 20 thread straightening rolls.

2. In a machine of the character stated, 25 the combination of guide rollers for guiding a web of fabric, with a weft straightening roll having its greatest diameter adjacent to the middle of its length and tapering therefrom toward each end, guiding means for the fabric parallel to said weft straightening roll for supporting the fabric when the said weft straightening roll is moved against 30 the fabric and between the said guiding means, and means for adjusting the weft straightening roll.

3. In a machine of the character stated, 35 the combination of guide rollers for guiding a web of fabric, with a weft straightening roll having its smallest diameter adjacent to its middle portion and the diameter increasing gradually from the middle portion toward each of its ends, guiding means for 40 the fabric parallel to said weft straightening roll for supporting the fabric when the said weft straightening roll is moved against the fabric and between the said guiding means, and means for adjusting the weft 45 straightening roll.

4. In a machine of the character stated, 50 the combination of a plurality of guide rollers for guiding a web of fabric, with means for straightening the weft threads of the fabric comprising a weft thread straightening roll having its largest diameter at the middle and tapering toward its 55 ends and movable against the fabric and between two of the guide rolls, a second weft straightening roll parallel to the first mentioned weft straightening roll and having its smallest diameter adjacent to its middle portion and gradually increasing from the center toward each end and movable 60 against the fabric and between two of the guide rolls, independent means for adjusting the two weft thread straightening rolls, a third weft thread straightening roll of cylindrical form, and means adjusting the 65 ends of said roll independently, whereby

said roll is movable against the fabric and between two of the guide rolls and with capacity for applying greater pressure toward one edge of the fabric than the other, and vice versa.

5. In a machine of the character stated, 70 the combination of guide rollers for guiding a web of fabric, with a weft straightening roll having its greatest diameter adjacent to the middle of its length and tapering 75 therefrom toward each end, guiding means for the fabric parallel to said weft straightening roll for supporting the fabric when the said weft straightening roll is moved against the fabric and between the said guiding means, 80 means for adjusting the weft straightening roll, a weft straightening roll of cylindrical form, and means for adjusting the ends of said roll independently, whereby said roll is movable against the fabric and between 85 two of the guide rolls and with capacity for applying greater pressure toward one edge of the fabric than the other, and vice versa.

6. In a machine of the character stated, 90 the combination of guide rollers for guiding a web of fabric, with a weft straightening roll having its smallest diameter adjacent to its middle portion and the diameter increasing gradually from the middle portion 95 toward each of its ends, guiding means for the fabric parallel to said weft straightening roll for supporting the fabric when the said weft straightening roll is moved against the fabric and between the said guiding means, 100 means for adjusting the weft straightening roll, a weft straightening roll of cylindrical form, and means for adjusting the ends of said roll independently, whereby said roll is movable against the fabric and between two 105 of the guide rolls and with capacity for applying greater pressure toward one edge of the fabric than the other, and vice versa.

7. In a machine of the character stated, 110 suitable upright frames having three horizontal guides at each end, adjustable bearings guided upon said guides, manually controlled means for adjusting the bearings upon their guides, a plurality of guide rolls arranged one above each other, a weft 115 straightening roll having its greatest diameter adjacent to its middle and tapering toward each end and journaled in one set of the bearings so as to be movable horizontally between two of the guide rolls, a second 120 weft straightening roll having its smallest diameter adjacent to the middle and gradually increasing in diameter toward each end and journaled in another set of the bearings so as to be movable horizontally between two 125 of the guide rolls, a third weft straightening roll of cylindrical form journaled in the remaining pair of bearings so as to be movable horizontally between two 130 of the guide rolls, and independent means

for adjusting the bearings supporting the cylindrical roll, whereby either end thereof may be moved to a greater or less extent than the other end, whereby said roll may 5 assume an oblique direction in a horizontal plane relatively to the guide rolls.

8. The herein described method of straightening weft threads displaced in curved position in a web of fabric, consisting in feeding the web of fabric in contact with a 10 rotary moving surface having similar surface speeds at substantially the same distances from each of the selvages of the

fabric, and in which the speed of the surface varies gradually and similarly at each side 15 of the middle of the web of fabric, whereby curved weft threads may be straightened transversely of the fabric either by an advancing or a retarding action which is most pronounced at the middle and gradually 20 lessening toward each selvage.

In testimony of which invention, I hereunto set my hand.

WM. S. ROWLEY.
